Primary Examiner — Stella Reid*Assistant Examiner* — Derrick Holland(74) *Attorney, Agent, or Firm* — Byrne Poh LLP(57) **CLAIM**

The ornamental design for a solar power generation assembly, as shown and described.

DESCRIPTION

FIG. 1 is a left side elevation view of a solar power generation assembly showing my new design;

FIG. 2 is a front elevation view thereof;

FIG. 3 is a left and bottom side perspective view thereof;

FIG. 4 is a left and back side perspective view thereof; and,

FIG. 5 is a top and left side perspective view thereof.

The broken lines shown represent unclaimed subject matter and form no part of the claimed design.

The broken lines immediately adjacent to the claimed areas in the views represent the boundaries of the design. None of the broken lines for any part of the claimed design,

APPLICATION NO. : 29/392448
DATED : April 17, 2012
INVENTOR(S) : Laurence Mackler

Page 1 of 1

It is certified that error appears in the above-identified patent and that said Letters Patent is hereby corrected as shown below:

On the title page, below item (57), in the DESCRIPTION, lines 10-11,
"None of the broken lines for any part of the claimed design" should be --None of the broken lines
form any part of the claimed design--.

Signed and Sealed this
Twenty-ninth Day of March, 2016
